LIGHTING FIXTURE GLOBE

David Glen Cameron, Rte. 1, Beaver, Pa.

Filed Feb. 12, 1960, Ser. No. 59,374

Term of patent 14 years

(Cl. D48—16)

Figure 2 is a bottom plan view showing substantially one-half of the globe and it being understood that the portion of the globe not shown has the same appearance as the portion shown.

I claim:

The ornamental design for a lighting fixture globe, as shown and described.
